WITNESS:

Harry R. Hodge,
INVENTOR
BY *Victor J. Evans*
ATTORNEY

UNITED STATES PATENT OFFICE.

HARRY R. HODGE, OF BROOKLYN, NEW YORK.

SCREW-ACTION WRENCH.

1,366,801.

Specification of Letters Patent. Patented Jan. 25, 1921.

Application filed August 7, 1920. Serial No. 401,921.

To all whom it may concern:

Be it known that I, HARRY R. HODGE, a citizen of the United States, residing at Brooklyn, in the county of Kings and State 5 of New York, have invented new and useful Improvements in Screw-Action Wrenches, of which the following is a specification.

This invention relates to screw action wrenches, and one of the principal objects 10 is to provide a wrench of this type with an outer jaw which is permitted a limited amount of swing or cant with relation to the other of the jaws.

Another object is to produce a device of 15 this nature which shall be simple of construction, cheap to manufacture, and durable and efficient in use.

Other objects will appear from the following description and claims. 20 My invention is embodied in a device which is fully illustrated in the accompanying drawing consisting of one sheet, in which:—

Figure 1 is a side elevation of my improved wrench.

Fig. 2 is a sectional view on line 2—2, Fig. 1.

Fig. 3 is a sectional view on line 3—3, Fig. 1.

Like characters of reference refer to like parts in the several views.

This invention contemplates the providing of a wrench of the type commonly used on pipes, rods and the like, said wrench to 35 be provided with a swinging jaw so as to effect a canting for obtaining a more secure hold on the article grasped. The teeth of the jaws are faced in opposite directions for aiding in bringing about this result.

Referring more particularly to the drawings, 1 is a main member of the device and comprises a hollow handle portion 2, which is knurled as shown in Fig. 1. Member 1 also comprises a threaded portion 3 and a 45 circular head 4 below which is an annular groove 5.

A nut member 6 is provided with a threaded aperture for co-action with the thread 3, and is slotted at 7 for the passage 50 of the lower end of the shank 8 of a jaw member 9. Shank 8 is pivoted in slot 7 by pin 10.

A jaw member 11 is provided on its upper face with forwardly inclined teeth 12 and on its lower face with an aperture 13 having shoulders 14, into which aperture

the head 4 is shrunk. The member 3 projects rearwardly and is provided with a slot 15 which is greater from front to rear than the breadth of the shank 8 which passes 60 through this slot, thereby permitting jaw member 9 a limited amount of front-to-rear movement with relation to member 11.

The teeth 16 of member 9 are faced rearwardly or in the direction opposite to the 65 teeth of member 11.

The operation of the device is as follows:—

When the wrench is to be used, the jaw 9 is canted rearward so as to provide a U-shaped or wedged opening into which the pipe or rod is introduced, the handle 2 being turned until both jaws are forced into intimate contact with the pipe or rod. Upon 70 now forcing forward on handle 2, the position of the teeth 12 and 16 will prevent the jaws of the wrench from slipping around the surface of the pipe or rod, and in consequence the teeth will bite into the object 75 obtaining a secure hold.

While I have described what I deem to be the most desirable embodiment of my invention, it is obvious that many of the details may be varied without in any way departing from the spirit of my invention 80 and I therefore do not limit myself to the exact details of construction herein set forth nor to anything less than the whole of my invention limited only by the appended 85 claims.

What I claim as new and desire to secure 90 by Letters Patent is:—

1. A wrench comprising a pair of jaw members one provided with a shank and the other with a slot, the shank of one of 95 said members passing freely through the slot in the other of said members, and said slot being greater in length than the breadth of said shank.

2. A wrench comprising a handle member 100 having a screw-threaded portion and a circular headed portion formed integrally therewith, a jaw portion shrunk onto said headed portion to turn thereon, and a second jaw portion having its shank passed 105 freely through the first said jaw portion, the first said jaw being provided with a slot which is greater in length than the width of the shank of the second said jaw portion.

3. In a device of the class described, the 110 combination of a member comprising a

handle, screw and head portions formed integrally; a nut member mounted on said screw portion; a jaw member mounted on said head portion and provided with a slot 5 in rear thereof; and a jaw member pivoted to said nut member and extending through said slot in the first said jaw member and

movable transversely of said slot, said jaw members being provided with oppositely facing teeth as and for the purpose set forth.

In testimony whereof I have affixed my signature.

HARRY R. HODGE.
